(No Model.)

E. M. PARKHURST.

BURNISHING MACHINE FOR BOOTS OR SHOES.

No. 353,756.

Patented Dec. 7, 1886.

FIG. 1

FIG. 4

FIG. 5

FIG. 2

FIG. 3

UNITED STATES PATENT OFFICE.

EMMONS M. PARKHURST, OF PHILADELPHIA, PENNSYLVANIA, ASSIGNOR TO
THE CHAMPION SHOE BURNISHING MACHINE COMPANY.

BURNISHING-MACHINE FOR BOOTS OR SHOES.

SPECIFICATION forming part of Letters Patent No. 353,756, dated December 7, 1886.

Application filed January 2, 1886. Serial No. 187,332. (No model.)

To all whom it may concern:

Be it known that I, EMMONS M. PARKHURST, a citizen of the United States, residing in the city and county of Philadelphia, State 5 of Pennsylvania, have invented a new and useful Improvement in Burnishing-Machines for Boots or Shoes, of which the following is a specification.

My invention has reference to a burnishing-machine for boots and shoes; and it consists in certain improvements, fully set out in the accompanying drawings, which form part thereof.

My object is to provide a burnishing-machine with a blunt V-shaped burnisher, formed substantially as shown, whereby a pointed part may be obtained to enable the burnishing of the smallest as well as the largest of shoes.

20 My object is also to so construct the machine that the boot or shoe is pressed upward against the burnisher and the upward thrust thereon is received by suitable anti-friction guide-rollers or their equivalents.

25 In the drawings, Figure 1 is a plan view of a burnishing-machine embodying my improvements. Fig. 2 is a side elevation of same. Fig. 3 is a perspective view of the burnisher removed from the machine. Fig. 4 is a cross-section on line $x-x$ of the burnisher, and Fig. 5 is a perspective view of the crank-head.

30 A is the frame of the machine. B is the crank-shaft, and is journaled therein. C is a band-wheel secured to said shaft, and D is the 35 crank-head, which is provided with T-shaped slot d across its face. Adjustably secured in said slot d is the crank-pin E. This crank-pin is connected by a link, F, with the reciprocating guide-shaft G, working through the 40 bearing H, and carrying upon its outer end the burnisher-frame I, in which the burnisher J is secured.

45 The burnisher-frame is provided with guides K on its side, and preferably over the connections with the burnisher. These guides K work against the anti-friction rollers L, journaled on stationary bearings secured to the brackets M, which brackets are bolted to the main frame of the machine. As the burnisher 50 is reciprocated the upward thrust, due to the

pressure of the shoe or boot, is received by the rollers and prevented from coming upon the guide shaft G, preventing it wearing upon its bearing and binding. N is a gas pipe from which a number of small gas-jets burn, the 55 flames projecting toward the rear or enlarged part, O, of the burnisher to keep it at uniform temperature.

The burnisher is shown in perspective in Fig. 3, and in section in Fig. 4, from which 60 figures its shape may be deduced. In cross-section it consists of the enlarged or semicircular back portion, O, and the forward or edge portion, P, connected by the flattened sides R, and this burnisher is made blunt V-shaped, 65 so as to provide the point Q, by which it may enter the smallest recesses or curves, and thus be suitable for large as well as small boots or shoes.

It is necessary in cases when shoes and slippers are made with galloon or English channel finish to provide the small rounded portion q on the front or pointed edge, Q, of the burnisher, and said portion q is provided with a guide-edge, q' , against which the outer edge 70 of the sole is placed to guide the sole, so that its under surface close to the edge may be burnished. If the guide edge or projection q' were not used, there would be liability of the shoe slipping to one side and the round portion q burnishing that portion of the sole required to be with a dead finish, and again, it reduces the care required by the operator, and thereby facilitates the work, increasing the production. Besides the above, the juncture 75 of the parts q q' forms a clean corner, which gives to the lower edge of the sole a highly-finished appearance.

It is immaterial to my invention what particular construction of a crank or crank-pin 80 is provided so long as the throw of the crank is made adjustable. For instance, in place of the crank-pin working in the T-shaped slot of the crank-head and being bound therein by a nut, a screw (indicated on dotted lines) may 85 be provided to move said crank-pin nearer or farther from the center of the shaft. Neither do I limit myself to the particular construction of burnisher-frame and its connection with the crank-head. Therefore, while I 90

prefer the construction shown, the details thereof may be modified in various ways without departing from my invention.

Having now described my invention, what I claim as new, and desire to secure by Letters Patent, is—

1. The burnisher J, made blunt V shape, substantially as shown, and for the purpose specified.
2. The burnisher J, made blunt V shape, and having its rear edge thick, as at O, and forward edge sharp, as at P, substantially as and for the purpose specified.

3. The burnisher J, made blunt V shape, and having its rear edge thick, as at O, and forward edge sharp, as at P, and provided with the curved part q and guide part q', substantially as and for the purpose specified.

4. A burnisher for boots and shoes provided with the small curved part q and guide q', arranged substantially as and for the purpose specified.

EMMONS M. PARKHURST.
